UNITED STATES PATENT OFFICE.

FRANK W. WILLIAMS, OF CHICAGO, ILLINOIS.

PANEL CONSTRUCTION.

1,289,029.

Specification of Letters Patent. Patented Dec. 24, 1918.

Application filed August 21, 1917. Serial No. 187,468.

To all whom it may concern:

Be it known that I, FRANK W. WILLIAMS, a citizen of the United States, and a resident of the city of Chicago, in the county of 5 Cook and State of Illinois, have invented certain new and useful Improvements in Panel Construction; and I do hereby declare that the following is a full, clear, and exact description of the same, reference being had 10 to the accompanying drawings and to the numerals of reference marked thereon, which form a part of this specification.

This invention relates to an improved form of a panel construction or a cover 15 adapted for use in phonograph cabinets and other similar articles, said panel being so constructed that the parts thereof may be readily assembled to interfit with one another so that the panel board proper which 20 is common to all of the frame members projects above the upper edges of said frame members in the finished form of the panel construction.

It is an object of this invention to construct a cover for a phonograph cabinet 25 wherein the panel is adapted to project above the upper edges of the panel frame.

Another object of the invention is the construction of a framed panel embracing 30 a peripherally grooved panel adapted to interfit with grooved frame members in such a manner that the upper portion of the panel is disposed projecting above the upper edges of the frame members.

35 It is an important object of this invention to provide a panel construction wherein a panel is adapted to be joined with frame members by means of tongue and groove joints whereby the upper edges of the panel 40 are positioned projecting above the upper edges of the frame members.

Other and further important objects of the invention will be apparent from the disclosures in the specification and drawings.

45 The invention (in a preferred form) is illustrated in the drawings and hereinafter more fully described.

On the drawings:

Figure 1 is a top plan view of a panel 50 construction embodying the principles of this invention.

Fig. 2 is a reduced section taken on line 2-2 of Fig. 1.

55 Fig. 3 is an enlarged fragmentary section taken on line 3-3 of Fig. 1.

Fig. 4 is a fragmentary section taken on line 4-4 of Fig. 3.

As shown on the drawings:

The reference numeral 1, designates a panel or plate preferably made of wood but 60 of course adapted to be constructed of metal or any other suitable kind of material. Said panel is of rectangular shape and has formed in the peripheral sides thereof a continuous rectangularly cross-sectioned groove 65 2, disposed equidistantly between the top and bottom surfaces of said panel, although not necessarily so. The frame of the device is made of molding and comprises a plurality of stiles or rails 3, the ends of which are 70 cut at an angle of forty-five degrees with respect to the longitudinal edges thereof to permit said stiles to be fitted together at their ends at right angles to one another by miter-joints. The stiles 3, are formed with 75 the outer surface concave as denoted by the numeral 4, and have a large beading 5, integrally formed along the lower margin thereof and a small bead 6, formed on the upper margin. The inner margin of each 80 of the stiles 3, is flat and inclined upwardly and inwardly as denoted by the reference numeral 7. A groove is formed or cut longitudinally in the inner surface of each of the stiles 3, a short distance below the upper 85 inner edge of said stiles thereby affording a tongue or squared beading 8, which extends along the entire length of said stiles.

To form a panel construction, phonograph cover, or panel section, the stiles 3, are each 90 disposed with the squared beading 8, thereof engaged in the squared panel groove 2, formed in the peripheral sides of the panel 1, as shown in Fig. 3, with the angled ends of said stiles abutting one another to form 95 miter-joints as denoted by the reference numeral 9, thus forming a frame around the panel 1. The stiles 3, and the panel 1, may be rigidly secured to one another to form a rigid construction, by means of glue, screws 100 or any other suitable means. The corners of the frame may be secured together in a similar manner.

Due to the peculiar arrangement of the squared beadings 8, which engage in the 105 panel groove 2, the upper portion of the panel 1, projects above the upper edges of the stiles 3, as clearly shown in Fig. 3. The construction of the stiles 3, and the panel 1, is such that the same may be readily assem- 110

bled and secured together to form a rigid panel construction adaptable for use as a cover for musical instrument cases, and for many other suitable purposes.

5 It will of course be understood that any desired form of molding may be used for the frame stiles, other than the form described, and further that numerous other details of construction may be varied through 10 a wide range without departing from the principles of this invention, and I therefore do not purpose limiting the patent granted otherwise than necessitated by the prior art.

I claim as my invention:

15 1. In a hollow cover of the class described the combination of a tapered rim having an internal tongue and groove at the smaller end thereof, and a panel closing said smaller end and having a peripheral groove engaging said tongue of the rim and having a tongue at each side of the groove, one of which said tongues engages said groove of the rim and the other of which said tongues overlaps the smaller end of the rim.

20 2. In a cover of the class described the

combination of a tapered rim, a panel closing, and offset beyond the smaller end of the rim, said panel having a peripheral tongue and groove engaging a groove and tongue respectively in the inner face of the rim and having a wall of the groove overlapping the end of the rim.

3. In a cover of the class described the combination of a tapered rim comprising a plurality of strips secured together end to end and having an annular flange at the larger end and an annular bead at the smaller end, an internal tongue and groove at the smaller end of the rim surrounded by the said bead, and a panel closing the smaller end of the rim and having a peripheral tongue and groove engaging the internal groove and tongue respectively of the rim.

In testimony whereof I have hereunto subscribed my name in the presence of two subscribing witnesses.

FRANK W. WILLIAMS.
